UNITED STATES PATENT OFFICE.

JOHN WILLIS WARREN, OF AKRON, OHIO, ASSIGNOR OF ONE-FOURTH TO CASPER KAMMER, OF AKRON, OHIO.

WRENCH.

Application filed February 12, 1923. Serial No. 618,712.

To all whom it may concern:

Be it known that I JOHN W. WARREN, a citizen of the United States, residing at Akron, in the county of Summit and State of Ohio, have invented certain new and useful Improvements in Wrenches, of which the following is a specification.

This invention relates to wrenches and more particularly to ratchet wrenches.

An object of the invention is the provision of a ratchet wrench having a movable jaw which is adjustable on a threaded stem or handle.

A further object is the provision of a wrench of this character, which is of simple and durable construction.

In the accompanying drawings, I have shown one embodiment of the invention. In this showing:

20 Figure 1 is a side elevation,
Figure 2 is a front elevation,

Figure 3 is a transverse sectional view on line 3—3 of Figure 1,

Figure 4 is a similar view on line 4—4 of

25 Figure 1, and,

Figure 5 is a detail view of the movable jaw.

Referring to the drawings, the reference numeral 1 designates the shank of the wrench which is provided with a suitable handle 2 at its upper end. A stationary jaw 3 is formed on the lower end of the shank. The movable jaw comprises a substantially U-shaped member 5, adapted to surround the shank of the wrench. This U-shaped member is provided with a projecting lip or finger 6 at one end, adapted to be received in a groove 7, of an adjusting nut 8. The adjusting nut is provided with internal threads adapted to mesh with external threads 9 on the shank to permit longitudinal adjustment of the movable jaw. The U-shaped member 5 carries a pin 10 extending transversely and this pin serves as a support for the movable jaw. As shown, a movable jaw 11 is arranged between the sides of the U-shaped member and is provided with an elongated slot 12, for the reception of pin 10. The inner side of the jaw is provided with a shoulder 13, adapted to engage a ratchet tooth 14. A block 15 is arranged adjacent the rear end of the U-shaped member, forming a support for a spring 16 which bears against the rear

end of the movable jaw. The forward end 55 of the U-shaped member is provided with a pair of ears 17 forming a support for a guide member 18 which engages the outer face of the movable jaw.

In operation, the movable jaw is adjusted 60 along the shank of the wrench by revolving the adjusting nut 8. The U-shaped member 5 moves with the adjusting nut, due to the engagement of the finger 6 in groove 7. When the wrench has been adjusted and is 65 ready for use, the application of force to the handle 2 to tighten a nut causes the forward end of the movable jaw to move inwardly toward the shank, permitting the ratchet 14 to engage the tooth or shoulder 70 13. When the wrench is operated in a reverse direction, the forward end of the movable jaw is swung outwardly disengaging it from the ratchet tooth and permitting it to move rearwardly. Rearward movement 75 of the jaw is limited by the length of the slot 12. This rearward movement of the jaw permits the wrench to be turned in a reverse direction over the corners of a nut without engaging the nut, whereby a new 80 grip may be obtained without removing the wrench from the nut. When the wrench is again turned in the reverse direction, the forward end of the movable jaw moves inwardly to engage the ratchet 85 14, and the spring 16 forces the jaw forwardly to insure such engagement.

It is to be understood that the form of my invention herewith shown and described is to be taken as a preferred example of the 90 same, and that various changes in the shape, size, and arrangement of parts may be resorted to without departing from the spirit of the invention or the scope of the subjoined claims.

Having thus described my invention, I claim:

1. A ratchet wrench comprising a shank, a fixed jaw carried by said shank, a supporting member embracing said shank adjustably mounted thereon, a pin carried by said supporting member remote from said shank, a movable jaw having an elongated slot adapted to receive said pin to permit limited movement of said jaw with respect 100 to said supporting member, said jaw being provided with a ratchet tooth on its inner face, and a locking dog carried by said 105

supporting member to engage said tooth and retain said movable jaw in operative position.

2. A ratchet wrench comprising a shank, 5 a fixed jaw carried by said shank, a supporting member embracing said shank adjustably mounted thereon, a pin carried by said supporting member remote from said shank, a movable jaw having an elongated 10 slot adapted to receive said pin to permit limited movement of said jaw with respect to said supporting member, said jaw being

provided with a ratchet tooth on its inner face, a locking dog engaging said tooth, and a spring carried by said supporting member 15 and engaging said movable jaw to normally retain said dog and said tooth in engagement.

In testimony whereof, I affix my signature in presence of two witnesses.

JOHN WILLIS WARREN.

Witnesses:

JACOB HEDDESHEIMER,
CASPER KAMMER.
